UNITED STATES PATENT OFFICE.

WILLIAM F. KINGMAN, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

DESIGN FOR A HANDLE FOR SPOONS, FORKS, OR SIMILAR ARTICLES.

53,594.

Specification for Design.

Patented July 15, 1919.

Application filed April 5, 1919. Serial No. 287,843. Term of patent 3½ years.

To all whom it may concern:

Be it known that I, WILLIAM F. KINGMAN, a citizen of the United States, residing at Providence, in the county of Providence and State of Rhode Island, have invented a new, original, and ornamental Design for Handles for Spoons, Forks, or Similar Articles, of which the following is a specification, reference being had to the accompanying drawings, forming part thereof.

The figure in the drawing is a view of the obverse side of the spoon, showing my design.

I claim—

The ornamental design for a handle for spoons, forks, or similar articles, as shown:

WILLIAM F. KINGMAN.
